LIGHT-TRANSMISSIVE WALL STRUCTURE

Friedrich Karl Johnsson, Essen, Germany

Application January 23, 1958, Serial No. 710,791

Claims priority, application Germany February 1, 1957

2 Claims. (Cl. 72—42)

My present invention relates to wall structures of the type in which panels of transparent or translucent (generally vitreous) material are joined together with the aid of a rigid supporting framework.

The use of a simple framework of metal, reinforced concrete or the like, firmly bonded to the panels of light-transmissive material, is often undesirable since internal as well as external causes (e.g. shrinkage of the concrete, settling of the foundation) may give rise to considerable stresses between panels and framework or in the panels themselves, frequently resulting in the impairment of both. These drawbacks are only partially eliminated through the interposition between the panels and the framework, either before or during assembly, of an elastically deformable resinous layer capable of forming an adhesive bond with the glass; major deformative stresses, such as those resulting from the shifting of ground in regions of unstable topography (e.g. rock slides) or in the vicinity of industrial blasting sites and the like, cannot be sufficiently absorbed by this type of construction.

My invention has for its principal object the provision of an improved wall structure of the character referred to in which no objectionable transfer of stresses between framework and panels can occur.

A more particular object of this invention is to provide a wall structure in which a vitreous construction element is securely held in a framework through positive engagement of interlocking formations yet with sufficient play so that expansions, contractions and even some geometrical deformations of the framework will not be communicated to the vitreous element.

A feature of the present invention resides in the provision of a supporting grid, e.g. of metallic rods, in whose polygonal (e.g. square) openings respective construction elements or panels of vitreous material are held with the aid of elastically deformable connector strips secured to the framework. Advantageously, the connector strips are profiled to mate with complementary formations on the glass panels in a dovetail pattern. For easier assembly it is convenient in such cases to divide each connector strip into two halves which are subsequently cemented together by a suitable adhesive. It is also desirable that each strip extend substantially over the entire length of a side of an associated glass panel and that interstices remaining between adjoining strips and panels be filled with an elastic putty or cement. Moreover, each strip may support two glass panels on opposite sides of the framework.

The invention will be described in greater detail with reference to the accompanying drawing in which:

Fig. 1 is a front-elevational view of the wall structure according to the invention; and

Fig. 2 is a fragmentary sectional view, on a larger scale, taken on the line II—II of Fig. 1.

The light-transmissive wall structure shown in the drawing comprises a supporting grid 1 formed from in-

tersecting vertical and horizontal rods 2 and 2a. The square grid apertures formed by these rods are covered by square glass panels 3 which are held along their edges by vertical connector strips 4 and horizontal connector strips 4a of synthetic plastic material. Each of the connector strips 4 and 4a, respectively traversed in longitudinal direction by a rod 2 or 2a, is divided into two halves 4', 4" cemented together by a suitable adhesive 9. The strip halves 4' and 4" are formed with respective projections 7', 7" which together constitute two dovetail-shaped tenons extending on opposite sides of the grid 1. These tenons mate with complementary flange portions 5 on the panels 3, adjoining flanges defining a trapezoidal groove 6 receiving the tenons 7', 7". The rods 2 and 2a are lodged in semicircular grooves 8', 8", formed on the meeting surfaces of strip sections 4' and 4", which may also be filled with adhesive 9; the adhesive 9 may likewise occupy the void between adjoining panels 3.

20 The horizontal rods 2a with their connector strips 4a have been shown supported and maintained at their proper relative distance by spaced-apart columns 10 which may, if desired, be of transparent or translucent resinous material. The strips 4 and 4a may also be of transparent or translucent material and may be colored to match the glass panels 3 or to provide a distinctive ornamental effect. The rods 2 and 2a may be of metal, e.g. iron, or of a suitably hard plastic material.

It will be apparent that the subdivision of strips 4 and 30 4a into halves 4' and 4" enables a particularly easy assembly of these strips with the panels 3 and with the rods 2, 2a. It is, however, also possible to make these strips in a single piece, as by forming them with a hardened inner core clad in a more flexible layer defining the 35 tenons 7', 7". Naturally, the columns 10 may be dispensed with if other means are provided to fix the rods 2 and 2a (e.g. at their junctions) in their desired relative position.

While I have thus described a preferred embodiment 40 of my invention, various modifications thereof will readily be apparent to persons skilled in the art and are intended to be encompassed in the scope of the invention as defined in the appended claims.

I claim:

- 45 1. A wall structure comprising a plurality of intersecting rods forming a grid, a plurality of elongated connector strips of elastically deformable material carried on each of said rods, each of said connector strips consisting of two halves formed with aligned longitudinal recesses and adhesive means bonding said halves together with the respective rod imbedded in said recesses, each connector strip extending between a pair of successive junctions of said rods and being provided on opposite sides with longitudinally extending, dovetail-shaped tenons, and a plurality of glass panels covering the apertures of said grid on opposite sides of said rods, each of said panels being provided with inwardly facing peripheral flanges interlocking engaged by the tenons of respective connector strips.
- 50 2. A wall structure according to claim 1 wherein said halves of each connector strip meet in a plane bisecting the tenons of the strip.
